UNITED STATES PATENT OFFICE

JERRY W. STEVENS, OF CLOQUET, MINNESOTA

SULPHUR BURNER

Application filed March 24, 1930. Serial No. 438,296.

The present invention relates to sulphur burners, having particular reference to one for burning free sulphur, and one of the rotary type.

- 5 Among the various kinds of burners are the substantially horizontal rotary type to which the present invention relates. Burners of this class heretofore have included a wrought iron rotor shell with cast iron heads. 10 Sulphur is burned inside the shell. One difficulty with this type of burner is the failure of the wrought iron in use, making necessary, where such burners are used substantially continuously, an annual replacement of the 15 wrought iron portion. No replacement of the cast iron heads is necessary. The cast iron is more durable in sulphur burners than the wrought iron.

In that type of burner, the combustion 20 takes place only on the interior of the shell, and accordingly the combustion surface is limited. The shell is unduly long and large for its capacity in order to provide sufficient surface.

25 The present invention has for an object the provision of a compact, efficient, sulphur burner, with a large combustion surface, which consumes a minimum of power, and which is smooth and quiet in operation.

30 Another object of the invention is the provision of a burner in which the combustion surfaces may be provided by cast iron parts, in order to prolong the life of the burner.

Still another object of the invention is to 35 provide a construction which in operation permits limiting the supply of melted sulphur which is carried within the burner proper, and which aids in distributing the sulphur over the interior of the burner.

40 Various other objects and advantages of the invention will be apparent from the following description and explanation of the invention as it is preferably embodied in apparatus shown in the accompanying drawing, 45 in which

Fig. 1 is a front elevation, partly in vertical cross-section of a burner.

Fig. 2 is a view of the right end of Fig. 1.

50 Fig. 3 is a vertical cross section on the line 3—3 of Fig. 1.

Fig. 4 is a modified form of fin on the rotor.

The burner comprises a stationary housing 10, which is preferably cylindrical in form, resting on supports 11 and 12. The casing shown has a tubular body section made preferably of cast iron, such as a pipe section. To the ends of the pipe section are secured circular heads 13 and 14, also of cast iron, having concentric circular openings 15 and 16 therein. Extending through the openings 15 and 16 is a hollow rotor which on the inside of the housing is suitably open, as by perforations, to provide communication between the space inside the rotor and the annular space 55 between the rotor and the casing. The rotor is preferably of larger diameter than the openings 15 and 16, and comprises a cylindrical tube, such as a cast iron pipe section 17, into which numerous holes 18 have been drilled. The ends of the pipe section are closed, supported by, and extended by means of tubular headers 19 and 20 of lesser diameter, which extend through the openings 15 and 16 for support from outside the housing. 75

As will appear hereinafter, one end of the apparatus is the cool end, and the other end is a hot end. At the hot end, where hot sulphur gases are discharged, the rotor supporting means is adapted to avoid effects of the 80 heat from the rotating parts. Hence, the extension header 19 has on its neck-portion 19^a a spoked wheel 21 of considerable diameter, resting on trunnions 22 and 23 carried by brackets 24 attached to the support 11. The 85 end of the header 19 is capped with a flanged collar 25 which is adjustable longitudinally of the neck portion 19^a to vary a space 26 which normally exists between the collar and the end 27 of a gas conduit 28 registering 90 with the collar.

The cool end of the rotor may have a similar support, but it is more convenient and economical to provide a collar 30 with a roller surface 31 resting on trunnions 32 and 33 95 mounted on spindles 34 secured in a lug 35 cast on the header 14. The cool end also carries a driving gear 36 for driving chain 37. The end of the rotor header 20 is capped with a damper structure having relatively mov- 100

able parts 38 and 39 with registering closable damper openings 40 therein. A hand nut 41 tightens the parts in a fixed setting of the damper openings. By this damper air to the 5 interior of the rotor may be controlled.

The top of the housing is covered with a saddle-tank 45 into which sulphur may be piled, and in which it is melted by heat from the burner in operation. A pipe line 46 with 10 a valve 47 connects the tank to the housing by discharging melted sulphur into a cup 48, which drains into the housing through pipe 49. Thus sulphur in melted form may be introduced into the housing to form a pool 15 of sulphur in the bottom thereof.

On the outer surface of the rotor means is provided which extends into the annular space 50 between the rotor and the housing, for the purpose of dipping into the pool of 20 sulphur, for carrying sulphur above the level of the pool and around with the rotor, and for increasing the area of sulphur exposed for combustion. This means may take various forms. In order to keep a minimum of liquid 25 sulphur in the housing, and to permit a pool of shallow depth at the bottom of the housing, I prefer to use a helical fin 51 on the rotor. This fin acts upon the pool of sulphur into which it is immersed by raising some sulphur 30 in the rotation, and also by backing up some of the sulphur in the pool to form a portion with a greater depth in the annular space 50. The pool is preferably backed up toward the 35 hotter end of the burner. Hence the direction of the fin, and the direction of rotation are so related that the sulphur is backed away from the cooler end of the burner. The fin is slightly spaced from the housing as shown at 52, thereby to permit accumulation of dirt 40 or sludge and to permit the sulphur pool to flow toward the cool end to a limited extent without the backing-up action. Accordingly, the entire length of the rotor has its fin contacting liquid sulphur at the bottom of the 45 casing, and sufficient sulphur is picked up to wet the entire length of the rotor with molten sulphur.

In Fig. 4 a modified form of rotor is shown in which two fins 54 and 55 are rigidly formed 50 on the rotor at opposite sides. In the rotation, they splash into the pool of sulphur and carry some of it upwardly and around with the rotor. The sulphur on the outside runs through the holes 18 and then over the 55 inside of the rotor, with dripping across the rotor or with flowing over the interior surface of the rotor.

A clean-out hole and plate 56 may be provided at any convenient location, preferably 60 in the bottom, of the housing 10, for the removal of dirt and sludge which gradually accumulates from the sulphur.

In order to provide and control the supply of air to the burner various dampers may be 65 constructed in addition to the damper in the

cool end of the rotor. Considerable combustion takes place in the annular space, so that air may be admitted directly into that space through dampers such as 57, 58 and 59. The latter damper is located at the bottom of the 70 annular space, but slightly raised above the normal level of the sulphur pool.

In operation, free sulphur may be introduced, either solid or melted, into the furnace and combustion started. A supply of sulphur is maintained in the saddle-tank 45, in the bottom of which the sulphur melts from the heat of the housing. The flow of the melted sulphur into the housing may be controlled by the valve 47. The liquid sulphur is permitted to form a shallow pool in the bottom of the housing. The depth of the pool is such as to maintain in the burner a supply of liquid sulphur, picked up and distributed over the interior by the fin or fins on the rotor. The helical fin tends to push the pool back toward the hot end, and there increases its depth with the increase in fluidity of the hotter sulphur. Sulphur adheres to the fins and flows over the interior and exterior surfaces of the rotor, dripping through the holes 18, and forming a shower of molten sulphur. The speed of rotation may control the extent of the showering. The gases swirl about in the burner spaces and eventually fill the interior with burning gases forming sulphur dioxide which escape through the hot end of the rotor into the conduit 28. Some sulphur may be carried as vapor from the burner, and the adjustment of the space 26 permits the entry by suction of sufficient oxygen to care for completion of the burning of this sulphur vapor.

The furnace may be placed horizontally as shown, or it may be slightly tilted to cause the liquid sulphur on the rotor to drain somewhat toward the cooler end of the burner. The fins on the rotor may be increased in number, and the pitch of the helical fin may be varied to suit the speed of the rotor or the amount of backing up of sulphur which is desired. The rotor may be open by means other than the circular perforations 18 which are shown. Various other changes and modifications and numerous stages of adjustments may be effected without departing from the spirit and scope of this invention as expressed in the appended claims.

I claim:

1. A sulphur burner comprising in combination a closed housing, a hollow rotor in said housing having its ends extending through the housing, and means outside the housing to support said rotor, the ends of said rotor being open to provide communication to the interior of the rotor, means to feed sulphur into the housing, said rotor being perforated within the housing, means to admit air to the housing, and means to carry sulphur gases away from the housing.

2. A sulphur burner comprising in combination a closed housing, a hollow rotor in said housing having an open end projecting from said housing, means outside the housing for supporting said projecting end, said rotor having openings therein to provide communication between the space inside the rotor and the space outside the rotor and in the housing, means to introduce air into said communicating spaces, and means to feed sulphur into the housing.

3. In a sulphur burner, a closed housing, a hollow rotor within said housing having hollow ends projecting from said housing, means outside the housing to support said ends of the rotor, said rotor within the housing being perforated to provide communication between the spaces within and about said rotor.

4. In a sulphur burner, a closed housing, a hollow rotor within said housing, means to support said rotor for rotation, said rotor having a gas discharge end projecting from said housing and having its portion within the housing provided with openings to establish communication between the spaces within and about said rotor.

5. In a sulphur burner, a closed housing, a hollow rotor in said housing having a hollow end of reduced diameter projecting from said housing, means to support the rotor for rotation including means outside the housing for supporting the projecting hollow end, said rotor within the housing having openings to provide communication between the spaces within and about the rotor.

6. In a sulphur burner, a closed housing, a hollow rotor in said housing having hollow ends projecting from said housing, said rotor being enlarged in diameter within the housing and being perforated, and means for supporting the rotor for rotation.

7. A sulphur burner comprising in combination, a closed housing, a hollow perforated rotor within the housing, said rotor having an open hollow end projecting from the housing, means to feed sulphur into the housing, means to admit air to the housing, and means associated with the hollow projecting end for receiving sulphur gases therefrom.

8. A rotary sulphur burner comprising in combination a hollow rotor, means to feed air into one end of said rotor, means to receive hot gases from the other end of the rotor, a stationary housing about a portion of said rotor, said rotor being perforated in the region surrounded by the housing, means to feed sulphur into the housing, and means on the rotor adapted in the rotation of the rotor to pick up sulphur from the stationary housing and supply it to the rotor.

9. In a sulphur burner, in combination, a housing adapted to hold a pool of sulphur, a rotor adapted to rotate on a substantially horizontal axis in said housing and positioned

above the pool of sulphur, and a helical fin on the rotor adapted in the rotation of the rotor to move the sulphur in the housing in the direction of the length of the rotor whereby to increase the depth of the pool in one end of the housing.

10. In a sulphur burner, in combination, a housing adapted to hold a pool of sulphur, a rotor adapted to rotate on a substantially horizontal axis in said housing and positioned above the pool of sulphur, and propelling means on the outside of said rotor positioned to be immersed in said pool and to move sulphur axially of the rotor in the pool in the rotation of the rotor, whereby to increase the depth of the pool in a part of the housing.

11. In a sulphur burner, in combination, a stationary cylindrical housing, a rotor in said housing, each providing within it a space for burning sulphur, a saddle tank on said housing, and a valved connection from said tank into the housing for feeding melted sulphur into the housing, and means on the rotor for picking up sulphur from the housing for feed to the rotor.

12. A sulphur burner comprising in combination, a cylindrical housing, heads for closing the ends of said housing, a hollow cylindrical perforated rotor concentrically mounted in said housing, tubular ends of reduced diameter closing and supporting the ends of said rotor and projecting through said heads of the housing, means to support said ends for rotation, projecting means on the rotor in the space between the rotor and the housing, a damper in one of the rotor ends for admission of air, the other tubular end of the rotor providing an outlet for burned gases, and means to feed sulphur into the housing.

13. A sulphur burner comprising in combination, a cylindrical housing, heads for closing the ends of said housing, a hollow cylindrical perforated rotor concentrically mounted in said housing, tubular ends of reduced diameter closing and supporting the ends of said rotor and projecting through said heads of the housing, means to support said ends for rotation, a helical fin on said rotor in the space between the rotor and the housing, a damper in one of the rotor ends for admission of air, the other tubular end of the rotor providing an outlet for burned gases, and means to feed sulphur into the housing.

In testimony whereof I have hereunto affixed my signature.

JERRY W. STEVENS.
